UNITED STATES PATENT OFFICE.

ERIC SODERGREN, OF BROOKLYN, NEW YORK.

SOFA-BED.

SPECIFICATION forming part of Letters Patent No. 519,207, dated May 1, 1894.

Application filed December 4, 1893. Serial No. 492,681. (No model.)

To all whom it may concern:

Be it known that I, ERIC SODERGREN, of Brooklyn, in the county of Kings and State of New York, have invented a new and useful Improved Sofa-Bed, of which the following is a full, clear, and exact description.

My invention relates to an improved sofa bed, and has for its objects to provide a novel, convenient device of the character indicated, which will be of a compact construction, afford a receptacle at one end of the sofa, and provide a vertically adjustable spring bed within the frame of a sofa or lounge, that is connected with the sofa seat so as to be elevated, when said seat piece is elevated, and thus removed from the top of the sofa frame, and be automatically depressed by a return of the seat piece to a horizontal plane.

To these ends my invention consists in the construction of parts, as is hereinafter described and claimed.

Reference is to be had to the accompanying drawings, forming a part of this specification, in which similar figures of reference indicate corresponding parts in all the views.

Figure 1 is a broken plan view of the improved device showing the sofa top removed from the frame. Fig. 2 is a sectional side view on the line 2-2 in Fig. 1, showing parts adjusted to form a sofa or lounge. Fig. 3 is a sectional side view on the line 2-2 in Fig. 1, representing parts arranged to convert the sofa into a bed. Fig. 4 is a transverse sectional view, on the line 4-4 in Fig. 3. Fig. 5 is an inverted plan view of the sofa seat piece at its lower end; and Fig. 6 is a transverse sectional view taken on the line 6-6 in Fig. 5.

The main frame for the sofa and bed, consists of a box like structure 10, that is oblong and rectangular, having suitable dimensions for efficient service, said frame being preferably supported on casters. At the head of the frame 10, a chamber or receptacle 10^a, is formed by the introduction of a transverse partition 10^b, at a proper point, this chamber being convenient for the reception of bed clothing. Within the main portion of the frame 10, a spring bottom frame 11, is loosely fitted, which consists of a light strong frame that will easily slide in the part 10, and has the wire woven spring fabric 11^a secured in

taut condition on its upper surface. The length of the spring bottom frame 11, is so proportioned that a sufficient space will be afforded at each end of said frame for the attachment thereto of bracket-frames and grooved pulleys 12, that are rotatably supported by these bracket frames, the latter being fixed one near each side of the frame 11, at each end. The grooved pulleys 12, engage their peripheries with the ribbed projections of the guide strips 12^a, that are secured upon the lower end wall and the partition in the main box-shaped frame 10, at points which will permit the free vertical reciprocation of the bed bottom frame.

The frame 11 is sustained and vertically adjusted in the main frame 10, by duplicate mechanism, one set being placed on each side of the frames mentioned, and located in spaces provided for their introduction and free movement, and as the parts are alike for each side, the description of one set will answer for both.

In the space extending between the bed bottom frame and main frame before mentioned, two pairs of similar link plates 13, are pivoted by one end of each plate upon the side of the outer or main frame 10 and the inner frame 11, near the ends of the same. The end portions of each pair of link plates 13, that are adjacent have lapped contact and are pivoted together, and on the outer sides of said lapped parts the ends of a connecting bar 14, are jointed with the same rivets that pivot the link ends together.

The lounge or sofa seat piece 15 provided for the improved device, comprises a rectangular frame of such relative dimensions as will adapt it to conform with the upper edge of the main frame 10, whereon it is imposed when adjusted for use, and is suitably upholstered to fit it for its purpose. The frame of said part 15 is furnished with a bottom to retain the hair or other material used as cushion stuff in upholstering the same. At a proper distance from the end of the seatpiece 15, which in use is nearest to the foot of the main frame 10, two bent arms 16, are oppositely pivoted on the sides of the seat frame. Preferably, there are two similar longitudinally slotted bracket blocks 16^a, provided for the jointed connection of the arms with the

- seat frame, and these blocks which are affixed upon the lower edges of the frame, receive between their slotted portions the ends of said arms that are pivoted to the bracket blocks, 5 this provision affording a substantial and neat connection between the parts mentioned. The other extremities of the bent arms 16, are projected through the spaces formed between the sides of the main frame 10 and bed bottom frame 11, and are each pivotally connected to one end of a link bar 17, the opposite ends of these link bars being pivoted upon the sides of the connecting bars 14, near the longitudinal centers of the latter. When the 10 seat piece 15, is adjusted as shown in Fig. 2, the bed bottom frame will be lowered within the main frame 10, and the links 13 together with their attachments, will be folded together as therein represented.
- 20 It will be seen that by the construction and arrangement of parts hereinbefore described, the rearward and upward movement of the seat piece, to dispose it in an upright position at the foot of the main frame 10, will 25 cause the pairs of links 13, to be spread apart, and the bed bottom frame 11 to be correspondingly elevated, the degree of such a vertical movement being gaged by the relative proportion of the parts which effect it, so 30 that the wire woven top 11^a, will lie about level with the upper edge of the main frame 10, when the seat piece 15 is slightly inclined rearward from a vertical position, as represented in Fig. 3.
- 35 When the parts are adjusted as just described, a mattress 18, may be laid upon the woven wire fabric 11^a, and a comfortable bed be thus afforded, to complete which the usual bed covering should be added.
- 40 At the head of the main frame 10, a lid 10^c is hinged upon the top edge so as to adapt it to be swung up, and on the lid a pillow or 45 head rest 10^d is formed or secured, which may be furnished with interior springs as a yielding foundation for upholstering, as indicated in Figs. 2 and 3, this head rest serving for the sofa and bed, as an elevated yielding support for the head of an occupant.
- 50 When the parts are to be arranged for serving as a sofa having a single head piece, the seat frame is rocked into a horizontal position so as to dispose it upon the top edge of the main frame 10, and to facilitate the swinging of the seat frame or piece, anti-friction 55 rollers 19, are rotatably secured at the rear end of the main frame, and have their grooved peripheries engaged by the ribbed edges of track strips 19^a, which are attached to the lower side of the seat piece near its rear end, 60 this provision obviating wear and friction, when the heavy piece 15 is changed in adjustment as before explained.
- 65 In order to assist the movement of parts when the seat piece 15 is elevated, spiral springs 20, are placed at each end of the main frame 10, within it and between its bottom board and the bed bottom frame 11, these

springs being compressed as shown in Fig. 2, when the device is adjusted to form a sofa, their energy being exerted to throw up the 70 frame 11, when the seat piece 15, is erected into the position indicated in Fig. 3.

It is claimed for this device that it is compact and convenient, is readily convertible into a bed or sofa as occasion may require, 75 and that when arranged to provide a bed, the elevation of the woven wire bed bottom simultaneously effected with the elevation of the sofa seat piece, will so remove the bed frame from the floor of an apartment wherein the 80 device is located, that a healthy and comfortable bed will be provided, the change of adjustment to produce a bed or sofa being quickly effected without the use of tools.

In the chambers, or living rooms of small 85 houses or flats, room space is contracted in area, and an open bed, or ordinary folding bed cannot be conveniently used, nor can a bed lounge that folds outwardly at one side, as the increased width of the bed thus provided 90 may require the removal of other essential pieces of furniture from the room. This improvement is specially advantageous for use in such residences, as it affords a neat, commodious sofa for seating or reclining purposes 95 during the day, and a readily convertible single bed, that does not take up more floor space than the sofa, the vertical rocking movement of the seat piece 15, at the foot of the sofa frame serving to elevate the bed frame, and 100 as the seat frame may rest against a wall of the room, no available space is taken up by it when it is elevated into a vertical position.

Having thus fully described my invention, I claim as new and desire to secure by Letters 105 Patent—

1. The combination, with the main frame of a sofa or lounge, of a seat piece pivotally connected thereto to rock or swing on an axis that has movement longitudinally of the main 110 frame and is arranged transversely of the sofa frame, near the foot end thereof, so that the seat piece can be brought into an upright position at the foot end of the sofa, substantially as described.

2. The combination, with the main frame of a sofa or lounge, of a bed bottom frame having vertical sliding movement in the sofa frame, a seat piece having a pivotal connection with the sofa frame at one end thereof to swing in 115 a plane extending longitudinally of the sofa frame, the pivot of the seat having movement longitudinally of the main frame, and an operative connection between the seat piece and the bed bottom frame, substantially as and 120 for the purpose set forth.

3. The combination, with the main frame of a sofa or lounge, of arms pivotally connected with the said frame near one end thereof by means of pivots extending transversely of the 130 sofa frame, and a seat piece pivotally connected with the said arms at a suitable distance from one of its ends, whereby the seat piece can be swung in a vertical plane extend-

ing longitudinally of the sofa frame, to bring the seat piece into an upright position with its end portion resting against that of the sofa frame, substantially as described.

5. 4. The combination, with the main frame having a partition to form two compartments therein, of a bed bottom frame having vertical sliding movement in one of the said compartments, links having pivotal connections to the main frame and the bed bottom frame

respectively, rods connecting the links, a seat piece having a pivotal connection with the main frame, and an operative connection between the seat piece and the said rods, substantially as described.

ERIC SODERGREN.
